UNITED STATES PATENT OFFICE

JOSEPH PERCY REMINGTON, OF PHILADELPHIA, PENNSYLVANIA

MEANS OF CARBURETION

Application filed February 26, 1925. Serial No. 11,686.

This invention has reference broadly to systems of carbureting liquid fuels, while it relates more specifically to the gasifying of hydrocarbons for admixture with air as the explosive media used in internal combustion engines. Heretofore the production of a proper combustible mixture for use in internal combustion engines has been attended with difficulty in admitting liquid combustible properly proportionate to the varying demands incident to throttle opening and closing. Another difficulty is associated with the complete atomization of the hydrocarbon before entry into the combustion zone. Bearing in mind the recited objections, it is highly important that no fuel should enter the combustion chambers or even the intake manifold unless it is completely atomized. Concurrent with advancement in the art, and use of inferior grades of fuel, considerable attention has been devoted to improving the carburetors for supplying fuel; but here again, considerable difficulty has evidenced itself and become increasingly serious since the quality of fuel has steadily deteriorated. Under present practice, I have observed two apparently insurmountable perplexities to the successful operation of automobile motor metering-throttles; namely, the lack of means effective to turn-off the flow of fuel, when the motor is not running, other than the hand throttle—which a driver may readily forget—and means to automatically regulate the flow of fuel for any given position of said throttle.

An important object of my invention is to effectively overcome the above recited objections and disadvantages by supplying fuel direct to the sub-atmospheric side of an engine throttle through the medium of means which I preferably term an automatic load control or feed.

Another object is to feed the fuel direct to the point of greatest air restriction, and to automatically relieve said air restriction incident to the throttle opening.

With the foregoing objects in view, which will more fully appear as the nature of my invention is better understood, the same essentially consists in the novel means of car-

buretion hereinafter described, typically illustrated by the annexed sheets of explanatory drawings, and tersely recited in the subjoined claims.

In the drawings:—

Fig. I, is a conventional representation showing the application of my novel device to the intake manifold of an internal combustion engine.

Fig. II, is a plan view—to an enlarged scale—of what I term the *adapter* or metering throttle which forms the subject-matter of this invention.

Fig. III, is a sectional view, taken as indicated by the arrows III—III in Fig. II.

Fig. IV, is a vertical section, taken substantially as indicated by the arrows IV—IV in Fig. II.

Fig. V, is a plan view of a slightly modified form of the invention; and,

Fig. VI, is a sectional view, taken as indicated by the arrows VI—VI in the preceding illustration.

Referring more in detail to the drawings a standard type of automobile engine is comprehensively designated by the numeral 5, the intake manifold 6 whereof is fitted with a conventional elbow 7, to the lower end whereof my novel metering throttle—generally indicated at 8—is coupled. This device 8 comprises a cylindrical section 9, having an appropriate flange 10 at one end, whereby it may be coupled to the manifold elbow 7, or directly attached to the manifold 6; the other end of said section constituting the air inlet 11.

At opposed points across the section 9 I conveniently provide an integral bushing 12 and a cupped projection 13, the latter being internally screw-threaded to accommodate a removable plug 14, as well as embodying a nipple 15 to which the fuel feed pipe 16 is connected by means of an appropriate adapter coupling 17. Journalized across the cylindrical section 9 by a partially tubular shaft 18 is a butterfly or metering throttle 19, said throttle—as best understood from Figs. IV and VI—being pivotally supported to one side of its center line, thereby affording two unequal lobes 20, 21, the latter of

which is preferably counterweighted or thickened. Or, the metering throttle 19, may be made in two separate parts, as shown in Figs. V and VI, with the smaller lobe 20' fixed to the tubular shaft 18 while the larger or weighted lobe 21' is pivoted thereon through provision of hinge members 32; said lobes being normally retained co-planar under the action of a recoil spring 33 applied about the shaft 18, with the free ends impinging the upper faces of the lobes 20' and 21', as shown, so that the latter is afforded pivotal movement independent of the former, in an obvious manner. The metering-throttle 19, it will be understood, is destined, by virtue of its overbalanced eccentricity to offer sufficient resistance to free opening as will enable it to hold an almost closed position in a slow air stream but to occupy a wide open posture under a full speed air stream. Further, it is to be noted, the spring 33 is of suitable strength to yield whenever air pressure on the underside of the throttle 19 is sufficient to lift said throttle and hence such automatic changeability effectively establishes what I have hereinbefore referred to as the *load control*.

A manually operable lever 22 is freely journaled on the bushing 12 to prevent undue pressure being imparted to the throttle shaft 18, and it is provided with a protruding lug 23 fitted with a set screw 24, the end of which abuts a projecting member 25 rigidly collared or otherwise attached at 26 on the outer end of the throttle shaft 18. The shaft 18 is also provided with a cam member 27—housed within the hereinabove referred to cupped projection 13—that controls a pin or metering valve 28 reciprocable within the bore 29 of the nipple 15. This pin or metering valve 28, controls the feed of liquid fuel as later on explained, while it operates automatically with movements of the metering throttle 19; and manually, *for purposes of closure*. Attention is particularly directed to the fact that, the tubular shaft 18 is axially bored to provide a suitable emission orifice or orifices 30 for the liquid fuel.

From the foregoing it will be evident that the valve 28 is operated by movement of the throttle or butterfly valve 19, and not by the manual control 22, *except for purposes of closure*. From this, it will be self-evident, the two essentials for the successful use of control of the described type are positively ensured, since, when the motor 5 is not running the throttle 19 maintains the fuel valve 28 positively seated or closed whereby leakage is effectively prevented, even through the manual control 22 might be left open. Further in hill climbing in "high" at very low speeds the throttle 19 will remain sufficiently closed to cause adequate vacuum to exist in the manifold 6 to lift and spray the fuel. It is therefore obvious, that the

weighted throttle 19 will, by creating sufficient vacuum to lift and spray the fuel, effect a restriction which would reduce the volumetric efficiency of the motor 5 at high speed if too great a lift were required. In other words, with my device, engine speed is manually controlled by movement of the lever 22 which, when rocked counterclockwise (with respect to the showing) permits the screw 24 to press upon the projection 25 that is conveniently secured by a pin to the shaft 18. It is, therefore, apparent that operation of the lever 22, which is connected to either the usual throttle control or accelerator, positively closes the lobe 21 or 21', but does not *positively open it*, said opening being effected by differing air pressures acting upon it in opposition to gravity or spring influence.

Briefly, the operation of my novel metering throttle is as follows:—When the motor 5 is not running there will be no flow of fuel through the semi-tubular throttle shaft 18 since the weighted throttle 19 will automatically—by gravity or spring influence—maintain the pin or metering valve 28 closed. Now it will be obvious, that, immediately the starter button for the motor is pressed a vacuum will be created at the orifice 30 in the tubular throttle shaft 18. If the throttle 8 is entirely closed, the metering throttle 19 will be rocked or lifted to a point where the projecting member 25 engages the adjusting screw 24. Incident to the movement just described, the pin or metering valve 28 is freed to automatically open and furnish liquid fuel instantaneously under the influence of the vacuum—usually twenty inches—normally present in the manifold 6 under such conditions.

As best appreciated from Fig. III, if the orifice or orifices 30, in the tubular shaft 18, be—as shown—drilled completely therethrough it provides an initial air inlet through which the suction stroke of the motor 5 can draw air. On the other hand, if this orifice 30 connects only into the axial bore 31, on the engine side of the metering throttle 19, the action of the device will be substantially the same but the screw 24 must be adjusted to compensatively regulate a proper idling position for said throttle, as will be well understood by those conversant with the art without further explanation.

In practice I have found that with my device fuel may be lifted twenty feet, and completely blasted at the orifice 30, so that no excess supply is required, while no choke or heater has been necessary or used therewith.

When *idling*, only about one quart of fuel is required per hour in about the proportions of one part fuel to twelve parts of air. Since practically all the air that enters the intake manifold 6 must pass through the orifice 30—which is of suitable diameter—for *idling*, the fuel is completely blasted, while the

amount of fuel may be regulated by the adjusting screw 24; which is functional also to control the idling-gap for the metering throttle 19, the engine suction raising said metering throttle until the projecting member 25 engages therewith.

Again, when the motor is not running, the weighted or spring influenced metering throttle 19 tightly seats the valve 28 thus preventing leakage. This phase of my invention is of vital importance, as, otherwise, metering the fuel into the intake 6 above the throttle 19 would not be so successful, inasmuch as many drivers forget to turn off the manual control when leaving a car.

My invention is readily adaptable to all present fuel feed systems, whether gravity, pressure or pump, and when installed in oversize meets all the requirements of any known fuel feed device in itself, since the tests for priming, *idling*, and ordinary driving have been successfully proven, whereas "stunt" tests can be met by the oversize throttle with high compression.

Finally it is to be understood that changes may be made in the size and proportion of the several parts and details of construction without departing from the spirit, or sacrificing any of the advantages of the hereinbefore described invention. Accordingly, the right is hereby reserved to make all such changes, or other adaptations than the typified examples, which may be reasonably embraced within the scope of the subjoined claims.

Having thus described my invention, I claim:

1. A carbureting attachment for internal combustion engines comprising a cylindrical section with an integral bushing and an opposing cupped projection; an eccentrically journalled throttle supported in said section by a tubular shaft; a cam controlled fuel supply valve in the cupped projection; and means associated with the integral bushing aforesaid limiting automatic opening of the throttle in opposition to differing air pressures.

2. A carbureting attachment for internal combustion engines comprising a cylindrical section with an integral bushing and an opposing cupped projection; a throttle embodying unequal lobes, one of which is hingedly movable relative to the other, said throttle being mounted on a tubular shaft, fuel feeding means in the cupped projection aforesaid controlled by a cam on the tubular shaft and means limiting automatic opening of said throttle under the influence of differing air pressures exerted against the movable lobe.

3. A carbureting attachment for internal combustion engines comprising a cylindrical section with an integral bushing and an opposing cupped projection; a throttle embody-

ing stationary and movable lobes journalled by a tubular shaft in the cylindrical section; an air admission orifice directed across the shaft at right angles to its axis; a cam on the end of the shaft in the cupped projection controlling a fuel feed valve operative in a radial portion thereof; and means associated with the other end of the tubular shaft limiting automatic opening of the movable throttle lobe by the speed of air passing through the aforesaid section.

In testimony whereof, I have hereunto signed my name at Philadelphia, Pennsylvania, this 10th day of February, 1925.

JOSEPH PERCY REMINGTON.
